LAMP BASE OR THE LIKE

Robert Brewer, 428 E. 49th St., Chicago, Ill.

Filed May 17, 1963, Ser. No. 74,927

Term of patent 14 years

(Cl. D48—20)

FIG. 1 is a perspective view of a lamp base or the like embodying my new design;

FIG. 2 is an elevational view thereof; and

FIG. 3 is a sectional view taken on the plane of line 3—3 in FIG. 2 and viewed in the direction indicated.

I claim:

The ornamental design for a lamp base or the like, substantially as shown.
